UNITED STATES PATENT OFFICE.

ALLAN EDGAR JEANS AND PETER THOMAS HAYES, OF LIVERPOOL, ENGLAND.

METAL-POT OF TYPE-BAR-MAKING MACHINES.

1,332,842.

Specification of Letters Patent.

Patented Mar. 2, 1920.

Application filed June 24, 1919. Serial No. 306,499.

To all whom it may concern:

Be it known that we, ALLAN EDGAR JEANS and PETER THOMAS HAYES, subjects of the King of Great Britain, residing at Liverpool, in the county of Lancaster and Kingdom of England, respectively, have invented certain new and useful Improvements in or Relating to the Metal-Pots of Type-Bar-Making Machines, of which the following is a specification.

This invention has reference to the melting pots of machines for producing stereotyped lines or bars of type as a substitute for type setting, the said invention having for its object to provide such melting pots with a device which will prevent impure matter such as dross from mixing with the metal required for efficiently working the pot.

20 This device is designed with a view to retaining in its interior all impure matter from the metal with which the pot is from time to time replenished in the working of the machine.

25 The invention will be understood from the following description reference being had to the accompanying drawings, in which:—

Figure 1 is a general view of the device 30 with a part broken away.

Fig. 2 is a vertical section of a melting pot with our invention applied thereto.

Fig. 3 is a similar view showing a modification.

35 Referring first to Figs. 1 and 2, the device in question comprises a metal container or colander A made of steel or other suitable material which will not be destroyed by the molten metal in the pot B. This container or colander A is perforated with small holes such as C up to the working level D of the molten metal in the pot. It is immersed in the melting pot and shaped to sit rigidly at one side of the pot, and is of such form that 45 it does not interfere with the working parts of the machine.

Instead of charging new metal direct into the pot B and allowing it to mix haphazard with the metal and any dross that may be 50 already contained therein, the container or colander is charged with the new metal required either by hand or by an automatic arrangement. This container or colander being perforated and immersed in the molten metal in the pot acts as a strainer and

allows only the pure molten metal to flow through the perforations C but keeps back the impure matter or dross thus assuring that the pump and the working channels shall have a clean supply. By the straining action of the colander the impure matter is retained in the colander, thus preventing any blockage in the working parts of the machine. No skimming off of the dross is necessary, and therefore any robbing of the alloy of the very ingredients which are relied upon to give the metal the hardness necessary to produce suitable lines of type for printing is avoided. The colander is however from time to time say once a week taken 60 out of the pot and emptied of the dross contained therein and then replaced. This is a very important point because skimming is always liable to rob the metal of a certain quantity of the tin and antimony which are 65 relied on to give the metal its hardness. Consequently the present invention avoids robbing the metal of its body elements and enables better lines of type to be produced. Furthermore by the present invention the 70 pump plunger will run for three weeks or so without cleaning instead of having to be disassembled every twenty four hours as hitherto.

If desired the container or colander A 75 may be arranged to move up and down in the molten metal in the pot B as shown in Fig. 3. In this case the container or colander is attached to the pump plunger E by means of a rod F and arm G and thus sets 80 up an agitation of the molten metal in the pot. When the pump plunger moves up, the colander A moves up with it but when the plunger moves on its down stroke, it carries the colander with it also, so that a very 85 effective agitation of the molten metal in the pot is set up.

We declare that what we claim is:—

1. The combination with the melting pots of type bar making machines, of a perforated container or colander into which the type metal required is charged, such container being immersed into the pot and acting as a strainer to allow the pure metal to flow freely through the perforations and mix with the metal in the pot, but keep back the dross.

2. The combination with the melting pots of type bar making machines containing a pump plunger, of a perforated container or

100

110

colander into which the type metal is charged, such container being immersed in the pot, and means for connecting the said colander to the pump plunger so that the colander will move with the plunger and set up an agitation of the molten metal in the pot.

5 In witness whereof we have hereunto

signed our names this 6th day of June 1919,
in the presence of two subscribing witnesses. 10

ALLAN EDGAR JEANS.
PETER THOMAS HAYES.
